UNITED STATES PATENT OFFICE.

FRANK B. MALLORY, OF NEW YORK, N. Y.

CURTAIN-FIXTURE.

SPECIFICATION forming part of Letters Patent No. 284,454, dated September 4, 1883.

Application filed July 27, 1883. (No model.)

To all whom it may concern:

Be it known that I, FRANK B. MALLORY, a citizen of the United States of America, residing at New York city, in the county of New York and State of New York, have invented 5 certain new and useful Improvements in Curtain-Fixtures; and I do hereby declare the following to be a full, clear, and exact description of the invention, such as will enable others skilled in the art to which it appertains to 10 make and use the same, reference being had to the accompanying drawings, and to letters or figures of reference marked thereon, which form a part of this specification.

15 This invention has relation to certain new and useful improvements in curtain-fixtures which are especially adapted to be used upon vehicles, its primary object being to provide a curtain which will be held securely within 20 the casing and may be adjusted to different heights, the curtain-roll being provided at one end with a spool, over which passes a weighted cord, and the curtain with transverse weighted strips, which extend to the edge of the curtain 25 and pass into suitable grooves in the frame, whereby the parts are counterbalanced, so that the curtain will be retained in any position that it may be placed.

My invention also consists in providing a 30 window-curtain-frame with a roller and curtain held between frames or guides, which are pivoted within the main casing, so that said frame or guide, which carries the curtain, may be thrown out from the casing at an angle, 35 said roller being provided with a cord and weight, as will be hereinafter more fully set forth, and pointed out in the claims.

In the accompanying drawings, which illustrate my invention, Figure 1 is a perspective 40 view showing my improvement attached to the standards or body of a vehicle, the curtain being shown at an angle with said vehicle. Fig. 2 is a sectional view, and Fig. 3 is a front view.

A represents the rear of a vehicle, which is 45 provided with the usual side standards, to which my improvement is adapted to be applied.

B represents the curtain-roller, which extends from one standard to the other, and is 50 placed horizontally between the same. One end of this roller is provided with a suitable

metallic spool, C, with side flanges, which is attached to the curtain-roll in the usual manner. This spool C is provided with a cord, c, to the lower end of which is attached a weight, 55 W. To the sides of the standards are attached suitable guide-bars, b b, which, if desirable, may be placed on a suitable frame, which is pivoted to the side standards. The upper part of the standard in which the end of the curtain-roll and spool lies is recessed so as to provide two steps, x and y, the inner recess being for the reception of the spool, and is cut away at one side, so that the cord c may pass into the vertical passage for the weight, while the 60 other recess is of larger diameter and forms a 65 guide which leads the curtain into the grooves or guides on the frame, which is formed by the guide-bars. The inner guide-bars are curved at their upper portions, as shown, and the curtain D is of sufficient size or width to 70 extend into the groove between the guide-bars b b. This curtain D is provided with a suitable number of transverse strips or weights, E, which are secured to the same by suitable 75 pockets, which extend transversely across the curtain to a point about opposite the guide-strips b. The cord c, which is attached to the spool C, is wrapped several times around the same, and the standards of the wagon may be 80 provided with a groove, in which will play this weighted cord; or, if desirable, this cord may be laid over another pulley, so that the weight may descend at some other point rather than within the groove or box in the standard. 85 By providing the curtain with a number of transverse weighted strips, E, and a cord and weight, the curtain is rendered self-balancing, as when the curtain is wrapped around the wheel B the weight will be nearer the central 90 portion of the roll C, and will not exert as much force upon the same, and when the curtain is drawn downwardly the cord is nearer the outer periphery of the roll and exerts a greater force, which is counterbalanced by the 95 weighted strips hanging vertically from the roll. These strips E are secured to the curtain, so that they will not register with each other as the curtain is rolled up.

In some cases it is desirable that the rear 100 curtain of the vehicle may be used as an awning, and when this is desired the side strips,

b b, which act as guides for the curtain, are attached to a supplemental frame, (indicated by the letter *F* in the accompanying drawings,) which frame is provided at its upper portion 5 with caps or covers *G*, which extend over the ends of the curtain-roll and the spool. The cap which extends over the spool is provided with slots, through which the weighted cord passes, so as not to interfere with the operation 10 of the same, or said spool may extend within the wagon standard or frame. Near the lower end of this supplemental frame are attached jointed arms *f f* for the purpose of holding the supplemental frame at an angle, as will be 15 fully understood by reference to the accompanying drawings. The lower end of this supplemental frame is provided with means for holding the same securely in a vertical position or parallel with the standards of the wagon.

20 From the foregoing it will be seen that this invention is especially adapted to be used upon butchers' wagons or other vehicles in which articles are carried and which it is desirable to serve out from the rear of the vehicle, as the 25 curtains may be readily placed at any height, or may be adjusted so as to serve as an awning.

The weighted strip *E*, hereinbefore referred to, not only serves to counterbalance the curtains, but also to hold the same against 30 displacement, thereby dispensing with buttons and other means necessarily employed every time a curtain is adjusted.

I am aware that prior to my invention window-curtains have been provided with springs 35 and other means for raising and lowering the same, and I do not claim such as my invention; but

What I claim as new, and desire to secure by Letters Patent, is—

1. A counterpoised curtain provided with 40 transverse weighted bars attached at intervals to the same, in combination with a curtain-roll provided with a spool, over which passes a weighted cord, and supporting means, substantially as described, and for the purpose set 45 forth.

2. The curtain herein described attached to a horizontal roll provided with a spool and weighted cord, said curtain having transverse bars attached to the same, which bars slide in 50 a groove formed in a supporting frame, substantially as shown, and for the purpose set forth.

3. The improved curtain for vehicles, provided with transverse weighted strips, horizontal curtain-roll, and the spool attached to the end of said curtain-roll with a weighted cord and side guides, *b b*, the parts being pivoted within a frame at a point opposite the curtain-roll, and means for holding the guide-bars at an angle with the frame, substantially as shown.

4. The improved curtain-fixture for vehicles, consisting of a supplemental frame pivoted at its upper part to a main supporting-frame, 65 said supplemental frame being provided with jointed arms for the purpose of holding the supplemental frame at an angle, and means, *g*, for securing the lower end of the supplemental frame to the main frame, and a counterpoised 70 sliding curtain, substantially as shown, and for the purpose set forth.

In testimony whereof I affix my signature in presence of two witnesses.

FRANK B. MALLORY.

Witnesses:

E. W. JOHNSON,
JOHN E. BEALL.
